UNITED STATES PATENT OFFICE.

CLIFTON D. PETTIS, OF NEW YORK, N. Y.

BRAKE SHOE.

Application filed December 6, 1923. Serial No. 678,793.

To all whom it may concern:

Be it known that I, CLIFTON D. PETTIS, a citizen of the United States, residing in New York, in the county of New York and 5 State of New York, have invented certain new and useful Improvements in Brake Shoes, of which the following is a specification.

This invention relates to brake shoes but 10 more particularly to that type which has a shell of tough ductile metal incorporated in the cast body of the shoe. The primary object of the invention is to provide a simple and economical construction which is 15 stronger and more durable than devices of a similar character heretofore known.

Further objects are to anchor the downwardly projecting side and end walls of the shell within the body metal of the shoe, 20 to more securely hold the body metal portion within the shell, to protect the reticulated side and end walls of the shell, to increase the strength of the shell and therefore of the brake shoe without increasing the wear on the wheel, and in general 25 to provide an improved brake shoe.

The many other objects and advantages 30 of my invention will be better understood by reference to the following specification when considered in connection with the accompanying drawings illustrating certain selected embodiments thereof, in which:

Fig. 1 is a side elevation of an improved 35 brake shoe.

Fig. 2 is a top plan view of a shell blank. Fig. 3 is the same as Fig. 2, the shell 40 being reticulated.

Fig. 4 is a transverse sectional view of 45 the shoe shown in Fig. 1.

Fig. 5 is a longitudinal sectional view of 50 a portion of the shoe shown in Fig. 1.

Fig. 6 is a transverse sectional view of 55 the blank shown in Fig. 2.

Fig. 7 is a transverse sectional view of a 60 modified form of blank.

Fig. 8 is a top plan view of a modified 65 form of blank.

Fig. 9 is a transverse sectional view of a 70 flanged brake shoe incorporating a shell formed from a blank such as that shown in Fig. 8, and

Figs. 10, 11 and 12 are transverse sectional views of modified forms of brake 75 shoes.

Referring to the drawings and particularly 80 to Figs. 1 to 6 inclusive, the brake shoe

comprises a pan or shell 15 preferably of tough ductile metal, a cast body 16, a key lug 17 and end lugs 18.

In the present embodiment the shell 15 is formed from a blank such as 19 (Figs. 2 and 6) having a relatively thick central portion 20 and a thinner edge portion 21. The edge portion of the blank is then perforated or otherwise reticulated as at 22 (Fig. 3). 65 Openings as 23 and 24 may be provided in the shell for key and end lugs respectively. The reduction in thickness of the blank in the present embodiment takes place wholly on the top or outer face thereof, leaving 70 the under or inner face flat as illustrated. The outer face of the edge portion is thus offset from the corresponding face of the thicker or central portion of the blank. The reasons for this will be presently described. 75 This reduction may be abrupt, substantially as at 25 (Fig. 6) or gradual, substantially as at 26 (Fig. 7).

The reticulated blank 19 is next bent substantially on the dotted line 27 (Fig. 3), 80 into the usual pan shape (Fig. 1). This line is located within the portion 20 of the blank so that the thick metal extends around the bend substantially as indicated in Figs. 4 and 5. This provides a channel shape 85 which is of the thickest section of the shell and thus gives great strength to the shell. At the same time the portions of the thick part of the shell do not extend to such a depth as to come into contact with the wheel. 90 It is contemplated that the shoe will be removed from service before the same has worn beyond the thinner portions of the shell.

The offsetting of the outer face of the thin 95 portion of the shell from the corresponding face of the adjoining thicker portion in the manner described leaves a space which is filled by the body metal of the shoe during the casting operation as indicated at 28. 100 Thus the thin portions of the sides and ends of the shell are surrounded by the body metal of the shoe and all are securely held together by the metal extending through the perforations or reticulations in the shell as 105 at 29. The downwardly projecting sides and end walls are anchored within the body metal of the shoe. Furthermore, the body metal on the outer face of each of these walls protects the walls. This construction is of 110 especial value when the shoe is worn thin. In Fig. 8 of the drawings is illustrated a

blank 30 for a shell particularly designed for use in a brake shoe for locomotive driving wheels. Here the thin portion 31 only extends about one side and both ends of the thicker portion 32. A section of a completed shoe 33 of this type is shown in Fig. 9. The portion 34 of the back which extends over the flange does not come in contact with the wheel and consequently need not be of thinner section.

In Fig. 10 of the drawings is illustrated a modified form of shell in which the walls are of uniform thickness and the depending portions 35 are bent inwardly as at 36 to provide offset portions 37. The body metal of the shoe flows into the space 38 outside of the offset portions of the shell and thus causes these portions to be surrounded by this metal with the beneficial results previously described. The metal in the space 38 is united to the body of the shoe through the reticulations 39. In this embodiment the body metal of the shoe extends beyond the inside face of the depending portions 37 of the shell as at 38', and thus makes an anchorage which more securely holds the body metal in the shell. This is of especial advantage when the shoe is worn thin.

In Fig. 11 is shown a further modification in which the shell 40 is composed of a thick central portion 41 and thin edge portions 42, but this differs from the embodiment similarly illustrated in Fig. 4 in that the reduction in thickness of the shell takes place upon the inner or under face. The portions 42 of the shell are flush with the corresponding faces of the body of the shoe.

In Fig. 12 is illustrated a further modification in which the depending walls 43 are of relatively thin metal and bent inwardly, at 44, as in the embodiment shown in Fig. 10. The portion of the shell at 45 is of relatively thick metal but this thicker portion does not extend about the bend.

It will be evident from the foregoing description that my improved brake shoe is simple and economical in construction and stronger and more durable than those of a similar character heretofore produced. The additional strength provided by the extension of the thick metal about the bend does not result in increased wear upon the rim of the wheel as would be the case if the entire shell were made of such metal. The offsetting of the depending portions of the shell insures a better connection between the shell and body metal of the shoe and eliminates curling or rolling of the shell.

I have selected various embodiments of my invention to fully illustrate the principles involved but it should be distinctly understood that this is for the purpose of illustration and not limitation, for I am aware that the form and arrangement may be materially changed without departing

from the spirit of my invention and I reserve the right to make all such changes as fairly fall within the scope of the following claims.

I claim as my invention:

1. In a brake shoe, a reinforcing plate comprising a relatively thick portion having a relatively thin portion along one edge thereof and the thick portion of said plate bent along a line substantially parallel with said edge to form with the adjoining thin portion a flange on said plate.
2. In a brake shoe, a reinforcing shell comprising a plate of ductile metal having a relatively thick central portion and relatively thin portions along the side edges thereof, the thick portion of said plate being bent along lines substantially parallel with each of said edges to form with the adjoining thin portions the side walls of the shell.
3. In a brake shoe, a reinforcing shell comprising a plate of ductile metal having a relatively thick central portion and relatively thin portions along the end edges thereof, the thick portion of said plate being bent downwardly along lines substantially parallel with each of said edges to form with the adjoining thin portions the end walls of the shell.
4. In a brake shoe, a reinforcing shell comprising a plate of ductile metal having a relatively thick central portion and relatively thin portions along the side and end edges thereof, the thick portion of said plate being bent along lines substantially parallel with each of said edges to form with the adjoining thin portions the sides and end walls of the shell.
5. In a brake shoe, a reinforcing shell comprising a back and side walls, the side walls being of varying thickness.
6. In a brake shoe, a reinforcing shell comprising a back and end walls, the end walls being of varying thickness.
7. In a brake shoe, a reinforcing shell comprising a back, sides and end walls, the sides and end walls being of varying thickness.
8. In a brake shoe, a pan-shaped reinforcing shell comprising a ductile metal plate having a relatively thick central portion and relatively thin edge portions, the side and end portions of said plate being bent downwardly to form the side and end walls of the shell with the thick metal of the central portion extending around the bends and forming the upper portion of said walls.
9. In a brake shoe, a reinforcing shell of ductile metal comprising a back and side walls, the outer face of a portion of each of said side walls being offset from the corresponding face-joining portion thereof.
10. In a brake shoe, a reinforcing shell of ductile metal comprising a back, sides and end walls, the outer face of a portion of a

each of said sides and end walls being offset from the corresponding face of the adjoining portion thereof.

11. In a brake shoe, a reinforcing shell of ductile metal comprising a back, sides and end walls, the sides and end walls being reticulated and the lower portion of the outer face of each offset inwardly from the upper portion thereof.

10 12. In a brake shoe, a substantially channel-shaped reinforcing shell comprising a back and depending side walls, the lower portion of said walls being of reduced thickness.

15 13. In a brake shoe, a substantially channel-shaped reinforcing shell of ductile metal comprising a back and depending side walls, the lower portion of said walls being reticulated and of reduced thickness.

20 14. In a brake shoe, a reinforcing shell of tough ductile metal comprising a back and depending side walls, the lower portion of said walls being offset inwardly from the outer face of the shoe.

25 15. In a brake shoe, a reinforcing shell of ductile metal comprising a back and turned down sides and end walls, the lower portion of said sides and end walls being

offset inwardly from the outer face of the shoe.

16. In a brake shoe, a reinforcing shell of ductile metal comprising a back and turned down sides and end walls, the lower portion of the said sides and end walls being reticulated and offset inwardly from the outer surface of the shoe.

17. In a brake shoe, a reinforcing shell of tough ductile metal comprising a back and depending side walls, the lower portion of said walls being offset inwardly and surrounded by the body metal of the shoe.

18. In a brake shoe, a reinforcing shell of ductile metal comprising a back and turned down sides and end walls, the lower portion of said sides and end walls being offset inwardly and surrounded by the body metal of the shoe.

19. In a brake shoe, a reinforcing shell of ductile metal comprising a back and turned down sides and end walls, the lower portion of the said sides and end walls being reticulated and offset inwardly and the offset portion surrounded by the body metal of the shoe, said body metal extending through the reticulation in said shell.

CLIFTON D. PETTIS.
